UNITED STATES PATENT OFFICE.

JAMES M. S. BLAUVELT, OF BROOKLYN, NEW YORK.

COIN-CONTROLLED WEIGHING-SCALE.

SPECIFICATION forming part of Letters Patent No. 448,200, dated March 17, 1891.

Application filed April 21, 1890. Serial No. 348,823. (No model.)

To all whom it may concern:

Be it known that I, JAMES M. S. BLAUVELT, a citizen of the United States, and a resident of Brooklyn, Kings county, New York, have 5 invented certain new and useful Improvements in Automatic Weighing-Machines, of which the following is a specification.

One object of my invention is to simplify the construction of the parts that regulates 10 the action of the index-hand, and another object is to provide improved means for regulating or adjusting the main or balance springs of the machine.

The invention consists in the novel details 15 of improvement and the combinations of parts that will be more fully hereinafter set forth, and then pointed out in the claims.

Reference is to be had to the accompanying drawing, forming a part of this specification, 20 wherein the figure is a perspective view showing my improvements in position, the front part of the machine being removed.

Referring now to the accompanying drawing, the letter A indicates part of the casing 25 of a weighing-machine, which may be of suitable construction. Within the casing A at its upper part is secured a plate B, to which part of the mechanism is preferably secured.

D is a vertical rod extending from a suitable or ordinary scale-platform at the lower 30 part of the machine (not shown) preferably about up to the plate B, as shown. At its upper part the rod D preferably carries a cross-bar a, to which springs b are or may be secured, the upper ends of which springs b 35 are connected to a support d, preferably adjustable, as shown, said springs preferably passing behind the plate B. For the purpose of easily and accurately adjusting the springs b I connect their upper ends to swiveled

studs e, carried by the support d, and their lower ends each pass into a series of holes f f in the cross-bar a. The series of holes f f each preferably comprises two vertical substantially parallel rows of holes, and the coils of the springs b are adapted to be screwed into or passed through said holes, as shown. By turning the springs b their coils will be passed more or less through the holes f f, 45 and thereby the length of the springs between the cross-bar a and the support d can

be quickly regulated, whereby the tension of the springs can be correctly adjusted. The swiveled studs e permit the springs to be turned without injury to the coils. When I 55 speak of the bar a as having the holes f, I mean, of course, the part to which the spring b is secured.

The rod D carries a shelf or support g, that is adapted to support a vertically-movable 60 rod E, that is supported in suitable bearings h on the plate B, as shown. On the rod E is mounted a sleeve or slide F, that is adapted to have independent longitudinal movement on the rod E.

i is a shoulder or collar on the rod E, that limits the downward movement of the sleeve F on the rod E, and by which the sleeve F is moved up when the rod E rises. The upward movement of the sleeve F is limited and 70 regulated by an adjustable stop j, preferably carried by a bearing h, as shown. Said stop j may consist of a screw, as shown.

In order to prevent the sudden rising of the rod E and sleeve F from injuring the parts I 75 make the shoulder or collar i movable on the rod E and hold it in its proper position as follows: l is a stop or collar secured to the rod E, and m is a spring coiled on the rod E and pressing at one end against the stop l and at 80 its other end against the collar i, which presses said collar against a pin or the like n on the rod E, which limits the upward movement of said collar i on the rod E. The pin n passes through a slot o in the sleeve F, as shown. If 85 now the rod E and sleeve F rise suddenly and with much force, the sleeve F will be arrested by the stop j in the proper position while the rod E is free to rise slightly farther, the spring m being thereby compressed and acting to 90 cushion the blow.

The sleeve F carries a rack p, that gears with a pinion q on the arbor 2 of an index-hand G, said arbor being suitably journaled on the plate B, as shown. As the sleeve F 95 rises and falls the index G will be turned by said rack and pinion.

When the rod D and shelf g are in their normal positions—that is, when the scale-platform is unloaded—the rod D and sleeve F 100 will be held elevated and the index G be held at zero. When now a weight is put upon the

scale-platform, the rod D and shelf g descend to a degree corresponding to the weight on the platform and the rod E descends a corresponding amount, carrying down the collar i.

5 If the sleeve F were not now supported independently, it would also descend; but it is intended that the sleeve shall not descend until released by the entry of a coin. To accomplish this I provide the following arrangement: The sleeve F carries a ratchet or other rack r, that is adapted to be engaged by a pawl H, pivoted on the plate B, as shown. The pawl H is normally in engagement with the ratchet r, and thus keeps the sleeve F elevated and the index at zero when the rod D has descended by the lowering of the support g, as before stated. The pawl H is to be moved out of engagement with the ratchet r only by the action of a coin. For this purpose the 10 pawl H is connected with a lever I, so that when the lever I is lifted by a coin the pawl H will be moved out of the ratchet r. The lever I connects by a rod s with one end of a lever J, pivoted in the machine, as at t, the 15 opposite end of said lever coming under or within a coin-chute L, so that the weight of a coin may act to depress one end of said lever and thereby lift the rod s, lever I, and thus move the pawl H out of the ratchet r. The 20 means I have shown connecting the pawl H with the lever I, consists of a crank u hung on the pivot of the pawl H, which crank is jointed to an arm v depending from the lever I and jointed thereto, as shown.

25 The crank u may be rigidly secured to the pawl H; but I prefer to have a movable connection, as follows: The pawl H carries two pins or projections w, and the crank u carries a projection x that passes between the 30 two pins w, as shown; but the positions of said pins or projections could be reversed, if desired. When the crank u turns, its pin x, by acting against a pin w, will move the pawl H in a corresponding direction. I prefer to 35 place the pins w at a distance apart, so that the pin x may have a slight free motion before actuating the pawl H. This arrangement is such that if a coin or blank that is lighter than a proper coin—say one cent—be dropped 40 upon the lever J, it will only have force enough to raise the lever I part of the way, if at all, and during this movement the pin x will not act to move the pawl H, because it does not move far enough to encounter the 45 pin w, and therefore the sleeve F will not be released to indicate a weight. So, also, when the lever I is descending after the pawl H has been moved out of the ratchet r, the sleeve F is allowed time to descend to carry 50 around the index before the pawl is pushed by the pins w and x into the ratchet r. After the lever I has been raised to release the pawl H from the ratchet r it should descend gradually or be retarded, so as to give the sleeve 55 time to descend to turn the index. For this purpose I pivot to the free end of the lever I a ratchet a², that is adapted to engage a ratch-

et-wheel b², as shown. A light spring d², carried by the lever I, keeps the ratchet a² in gear with the wheel b². When the lever I is raised by a coin, the ratchet a² slips over the wheel b² without turning the latter; but when the lever I descends the ratchets a² b² lock, and thus the ratchet-wheel b² will be turned. To retard the descent of the lever I the wheel b² connects by suitable gearing with a fan or regulator e². For this purpose I have shown a gear-wheel f², secured to the arbor of the wheel b², which wheel f² gears with a worm h², which carries the fan or regulator e².

80 The above parts are all suitably journaled in a frame 3, secured to the plate B, as shown.

In order to insure that the rod E will rise to its proper height every time to certainly bring the index to zero, I pivot a lever i² on 85 the plate B and place its free end under a projection or roller j² on the rod E, as shown. A light spring l², secured at one end to the lever i² and at its other end to the plate B, keeps the lever i² in contact with the projection j². m² is a rod guided in suitable bearings n² on the plate B, its upper end coming against the lever i², as shown. A pin o² on the rod m² limits the downward movement of said rod by contacting a bearing n². The 90 lower end of the rod m² is to be engaged by the shelf or support g, as shown, so that when the support g rises it will lift the rod m², and thereby the rod E will be pushed up to its proper height.

95 My improvements operate together as follows: When the parts are in their normal positions the pawl H will be in engagement with the ratchet r, the lever I will be down, and the index at zero, all as in full lines. A 100 person now steps on the scale-platform, which draws down the rod D and shelf or support g a certain distance, whereby the rod E will descend and rest on the shelf g. The collar i will also thereby descend, but sleeve F will remain elevated and the index thus be held at zero. The rod m² also descends when the shelf g descends, all as in dotted lines. A 105 coin now being dropped into the coin-chute it depresses the lever J, thereby raising the 110 lever I, which acts to turn the pawl H, to disengage it from the ratchet r, as before stated. The sleeve F being now free immediately descends until it comes to rest on the collar i. In its descent the sleeve F turns the index to 115 indicate the weight on the scale-platform, which indication is regulated by the distance the support g, and thereby the collar i, descends.

120 After the sleeve F descends the lever I immediately descends, and thus turns the pawl H back to engage the ratchet r, whereby the sleeve F can descend no farther until a new coin is inserted, and thereby a heavier weight than the one first applied will not be indicated for a single coin.

125 When the weight is removed from the scale-platform, the rod D rises, thereby pushing up the rod E, sleeve F, and rod m². The

sleeve F then becomes locked by the pawl H and remains so until another coin is inserted to release it.

Having now described my invention, what I claim is—

1. A sliding toothed bar, combined with a pawl arranged to engage said toothed bar, coin-actuated mechanism connected with said pawl for disengaging it from said toothed bar, and a movable connection between said pawl and said coin-actuated mechanism to allow the pawl independent movement, substantially as described.

2. The sliding rack p and the index actuated thereby and the sliding ratchet r, connected with and also actuated by and with the rack p, combined with the pawl H, to engage the sliding ratchet r, and coin-actuated mechanism connected with said pawl for disengaging it from said ratchet, substantially as described.

3. The ratchet r and the index in connection therewith, combined with the pawl H, crank u, pins or projections w x, and lever I, connected with the crank u, substantially as described.

4. The rods D and E, acting in unison, stop i on the rod E, sleeve F on said rod, index actuated by said sleeve, and ratchet r, connected with said sleeve, combined with the pawl H, lever I, and connections between said pawl and lever, substantially as described.

5. The rod D, having shelf or support g, and the rod E, having a stop i, combined with the sleeve F, an index actuated thereby, and an adjustable stop to regulate the upward motion of said sleeve, substantially as described.

6. The rod D, having shelf or support g, and the rod E, having loose collar i, rigid stop l, and spring m between said collar and stop, combined with the sleeve F, sliding on the rod E, a stop for the sleeve F, and an index actuated by the sleeve F, substantially as described.

7. The rod D, having shelf or support g, sliding rod E, having collar or stop i, sleeve F, having rack r, and an index actuated by

said sleeve, combined with the pawl H, to engage said rack, crank u, lever I, connected to said crank, and coin-actuated mechanism for lifting said lever to release the rack r, substantially as described.

8. The sliding rack F and an index actuated thereby, combined with the pawl H, to engage said rack, lever I, actuated by the entrance of a coin, and a movable connection between said pawl and the lever I, whereby the lever I can be moved a certain distance without actuating the pawl H, but by a further movement will actuate said pawl, substantially as described.

9. The sliding rack F and an index actuated thereby, combined with pawl H, crank u, projections w w, pin x, the distance between said projections being greater than the width of the pin x, lever I, connected with the crank u, and coin-actuated mechanism, substantially, as described, for lifting the lever I, substantially as specified.

10. The lever I, pivoted rack a², carried thereby, and spring d², combined with the toothed wheel b², regulator e², driven thereby, and coin-actuated mechanism for lifting the lever I, substantially as described.

11. The support d and spring b, swiveled thereto, combined with the bar a, having holes f, that receive the coils of the spring b, whereby said spring can be lengthened and shortened between a and d by passing its coils more or less through the holes f, substantially as described.

12. The support d, having swiveled stud e, and spring b, connected thereto, combined with the bar a, having holes f f, that receive the coils of the spring b, whereby said spring can be lengthened or shortened by passing its coils through said holes, substantially as described.

In testimony that I claim the foregoing as my invention I have signed my name, in presence of two witnesses, this 17th day of April, 1890.

JAMES M. S. BLAUVELT.
